(57) **CLAIM**

The ornamental design for a bottle, as shown and described.

DESCRIPTION

FIG. 1 is a perspective view of a bottle, showing a first embodiment of our new design;

FIG. 2 is a front elevational view thereof;

FIG. 3 is a side elevational view thereof;

FIG. 4 is a back elevational view thereof;

FIG. 5 is an opposing side elevational view thereof;

FIG. 6 is a top plan view thereof;

FIG. 7 is a bottom plan view thereof;

FIG. 8 is a perspective view of a bottle, showing a second embodiment of our new design;

FIG. 9 is a front elevational view thereof;

FIG. 10 is a side elevational view thereof;

FIG. 11 is a back elevational view thereof;

FIG. 12 is an opposing side elevational view thereof;

FIG. 13 is a top plan view thereof; and,

FIG. 14 is a bottom plan view thereof.

The broken lines shown in FIGS. 1, 6, 8 and 13 depict a portion of the bottle that forms no part of the claimed design.

1 Claim, 8 Drawing Sheets
